Patented Jan. 16, 1973

225,955

COMBINED ROOM DIVIDER AND STORAGE UNIT

Frank R. Torrey, 9805 Dallas Ave.,
Silver Spring, Md. 20901

Filed Feb. 19, 1971, Ser. No. 117,208

Term of patent 14 years

Int. Cl. D6—04

U.S. Cl. D6—189

FIG. 1

FIG. 3

FIG. 2

FIG. 4

FIG. 1 is a perspective view of a combined room divider and storage unit, showing my new design;

FIG. 2 is a rear elevational view thereof;

FIG. 3 is a left side elevational view thereof, and
FIG. 4 is a right side elevational view thereof.

I claim:

The ornamental design for a combined room divider and storage unit, as shown.
